UNITED STATES PATENT OFFICE.

EARL A. WHEELER AND WALLACE M. MORGAN, OF BAKERSFIELD, CALIFORNIA.

ROAD-PLANER.

1,236,518.

Specification of Letters Patent. Patented Aug. 14, 1917.

Application filed August 24, 1916. Serial No. 116,663.

To all whom it may concern:

Be it known that we, EARL A. WHEELER and WALLACE M. MORGAN, citizens of the United States, residing at Bakersfield, in the county of Kern and State of California, have invented certain new and useful Improvements in Road-Planers; and we do declare the following to be a full, clear, and exact description of the invention, such as will enable others skilled in the art to which it appertains to make and use the same.

Our invention aims to provide a simply constructed machine for improving the condition of oil macadam, petrolythic or even standard asphalt pavements which have been put down too soft and have therefore rolled or crept into waves in consequence.

Numerous machines have heretofore been designed for this purpose employing a series of cutting teeth and obliquely disposed blades in rear of said teeth, the teeth being adapted to cut off the high spots in the roadway while the blades are designed to distribute the material thus removed into the hollows. In so far as we are advised all machines of this class have been mounted on wheels and for this reason they have proven ineffective since the wheels in dropping into hollows and riding over ridges continually shift the cutting teeth and grading blades vertically. This renders it impossible for the roadway to be leveled with any degree of accuracy. To overcome this difficulty we rigidly mount the cutting teeth and the grading blades on a pair of parallel runners or skids and by so doing maintain a long bearing surface and thus prevent excessive vertical shifting of the teeth and blades.

In the accompanying drawing which constitutes a part of the application;

Figure 1 discloses a top plan view of the improved machine;

Fig. 2 is a vertical longitudinal section thereof; and

Figs. 3 and 4 are vertical transverse sections on the planes of the lines 3—3 and 4—4 of Fig. 1.

In specifically describing the construction shown in the drawings above briefly described, similar characters will be employed to designate corresponding parts throughout the several views and reference will be herein made to the numerous elements by their respective indices. To this end the numeral 1 designates a pair of spaced parallel runners whose lower edges and ends are pre-

ferably bound with metal straps 2 for resisting wear. At suitably spaced intervals the two runners are connected by tie bolts 3.

Bolted to the inner sides of the runners 1 near the inner ends thereof, are front and rear angle metal guides 4 and 5, said guides receiving therebetween a tooth carrying timber or beam 6 which is preferably laminated as shown in Fig. 2. The lower ends of adjusting bolts 7 are secured to the beam 6 in any appropriate manner, said bolts rising from said beam through openings in the crown bar of an arch 8, the legs of said arch being bolted or otherwise secured to the outer sides of the runners 1. Nuts 9 and 10 are threaded on the bolts 7 above and below the aforesaid crown bar and it will be evident that as said nuts are suitably adjusted the beam 6 may be moved vertically and then rigidly locked in adjusted position.

A plurality of parallel vertically disposed teeth or spikes 11 contact with the front and rear sides of the beam 6 and are so shaped at their lower ends as to cause them to plane or pare off the roadway with which they are brought into contact. To facilitate this operation, the front teeth are disposed opposite the spaces between the rear teeth as will be evident from Fig. 1. The teeth 11 may be secured in place in any suitable manner but clamping bars 12 are preferably used for this purpose, said bars having notches 13 in one edge which receive bolts 14, said bolts passing through the beam 6 as shown. Adjusting of the bolts 14 would obviously permit adjustment of the numerous teeth 11 and removal thereof for resharpening. When said teeth are to be removed, however, the bars 12 will be removed entirely. These bars are preferably provided with seats 15 which receive the teeth therein to prevent tilting of said teeth.

To effectively brace the front portion of the machine, a V-shaped brace rod 16 is bolted at its angle to the center of the beam 6 and is secured at its ends to the front tie bolt 3.

In rear of the beam 6, other beams 17 and 18 extend between the runners 1 and have their ends slidably received between angle metal guides 19 which are bolted to the inner sides of said runners. As shown the two beams 17 and 18 extend obliquely in opposite directions and the lower edges thereof are provided with blades 20, these blades being adapted to convey the material planed

off by the teeth 11 to the rear ends of said blades, gaps 21 being provided at such ends to permit this material to pass rearwardly. It will thus be evident that the material 5 prepared from the ridges of the roadway by the teeth 11 will be worked back and forth between the runners and will thus be distributed within the hollows. After this operation the highway may be covered with a 10 thin coating of sand or fine gravel and rolled after it has been used a suitable length of time.

The two blades 20 may be adjusted vertically by shifting the beams 17 and 18 between the guides thereof, this shifting being done by means of bolts 22 rising from the ends of said beams through the crowns of arches 23 whose legs are bolted to the runners 1, said crowns extending longitudinally 20 above the aforesaid beams and being similar in all respects to the crown 8 above described. Nuts 24 and 25 are threaded on the bolts 22 above and below the crowns of the arches 23 and serve to adjust the beams 17 and 18 and to lock them in the required positions.

By constructing the improved machine in the manner shown and described it will be comparatively inexpensive and durable, particular emphasis being laid on the fact that the teeth 11 and the oblique grading blades are held rigidly between a pair of parallel runners, this structure being of great advantage for the reasons heretofore set forth.

35 In the foregoing we have described a number of specific details of construction for accomplishing probably the best results and in the accompanying drawings such de-

tails have been illustrated, but it is to be understood that within the scope of the invention as claimed numerous changes may be made without sacrificing the principal advantages thereof.

We claim:

A road machine including a horizontal beam 45 extending transversely of the line of travel and having flat uninterrupted front and rear sides, a front and a rear series of straight one-piece vertical teeth contacting respectively with said front and rear sides 50 of the beam, upper and lower one-piece tooth clamping bars extending horizontally adjacent the upper and lower edges of the front and rear sides of the beam and having transverse grooves in their inner sides receiving the teeth, an upper series of bolts 55 passing through the upper clamping bars and through the intervening portion of the beam, and a lower series of bolts passing through the lower clamping bars and 60 through the portion of the beam between them, the front and rear series of straight one-piece teeth secured in contact with the front and rear sides of the beam serving the secondary function of preventing warping 65 of the latter as well as performing their primary function.

In testimony whereof we have hereunto set our hands in the presence of two subscribing witnesses.

EARL A. WHEELER.
WALLACE M. MORGAN.
